corporation of Illinois

Application June 8, 1953, Serial No. 25,374

Term of patent 14 years

(Cl. D55—1)

To all whom it may concern:

Be it known that I, Henry E. Frederick, a citizen of the United States, and a resident of Park Ridge, in the county of Cook and State of Illinois, have invented a new, original, and ornamental Design for a Punching Machine or Similar Article, of which the following is a specification, reference being had to the accompanying drawing forming a part thereof.

On the drawing:

Figure 1 is a front perspective view of a punching machine, showing my new design; and

Figure 2 is a rear end view of the device shown in Figure 1.

The other end of the punching machine from

that shown in Fig. 1 is like the end shown in Fig. 1.

I claim:

The ornamental design for a punching machine or similar article, as shown and described.
